TRUNKING SYSTEM OF RADIO DISTRIBUTION

Application filed March 26, 1925. Serial No. 18,529.

The present invention relates to systems of radio broadcast distribution and has for its object the organization of such a system so that a program may be originated, relayed and distributed over a large area, uniformly and in a systematic and orderly manner to authorized users or subscribers who will get the full benefit of the use of vacuum tubes in receiving and amplifying without the necessity of maintaining tubes at their stations; the tubes used by the subscribers in receiving being located at central points, where supervision, maintenance, power supply and control may be centralized and put under the control of expert operators.

The invention is applicable to manual, automatic or semiautomatic telephone systems, the principles involved not being changed by different methods of effecting or controlling the necessary electrical switching connections.

My invention is illustrated in the accompanying drawings, in which

Figs. 1 and 2 indicate diagrammatically, the telephone exchange portion and the broadcast distributing portion, respectively, of a subscriber's central station forming part of a system embodying my invention.

Fig. 3 is a modification of the broadcast, distribution switching system.

Fig. 4 is a further modification of the broadcast, distribution, switching system.

Figs. 5 and 6 are detail views of the operator's lamp and jack-switch strips.

Referring to the drawings in detail and first to Fig. 1, this shows the essential circuits of an ordinary telephone exchange system in which J—J' are line terminal jacks forming the terminals of telephone lines leading to stations to be interconnected such as the subscriber's station A'. These jacks are arranged to be interconnected through the usual answering and calling plugs P—P' forming the terminals of the usual common battery cord circuit shown. The central office terminals of each line are provided with the usual line relay L', line lamp L² and cut-off relay L³. Where service is to be metered a recording meter M is also individually associated with the line. Thus,

the circuit arrangement here shown is that of the standard multiple switchboard, common battery, telephone exchange system, and as such is well understood in the art further detailed description thereof will be here deferred and brought out later in the description of operation. In addition to the usual line terminal, multiples 1, 2 and 3, representing multiples of the tip, sleeve and test or cut-off circuits, respectively, I provide a fourth conductor 4 leading from a contact on the line relay along with the multiple conductors 1, 2 and 3 to the broadcast distributing system diagrammed in Fig. 2.

Fig. 3 shows the broadcast distributing system of which the portion to the left of the dotted line is situated at the central office and connected with the subscriber's telephone line terminal apparatus of the telephone central C (Fig. 1) through conductors 1, 2, 3 and 4, while the portion to the right of the dotted line in Fig. 2 is situated at the subscriber's substation and connected with the subscriber's telephone substation apparatus A' (Fig. 1) through the multiple conductors 5 and 6. In Fig. 2 the subscriber's line multiples 1—2 terminate in the spring contacts 7—8 of a jack 9 which contacts are arranged upon the insertion of the dummy plug 10 to be spread apart to engage with the stationary contacts 11—12 to extend the connection of the multiples 1—2 to conductors 13—14. The conductor 13 connects with the positive terminal of the common central office battery B through the winding 15 of a repeating coil 19 while the conductor 14 connects with the negative terminal of the battery B through a sleeve or supervisory relay 42 and the winding 16 of a repeating coil 20.

A radio receiving set, individual to the line, is arranged with its output circuit 21—22 connected in series with the windings 17—18 of the repeating coils 19 and 20, and the plate battery B². This receiving set comprises in general, a detector tube 23 and amplifying tubes 37 arranged with suitable circuit connections and other apparatus to form a simple regenerative receiver with one stage of audio-frequency amplification as shown. The detector tube has its tuned input circuit

24 coupled to an antenna 25 and its plate circuit 26 coupled to the input terminals of the amplifier tube 37 through an audio-transformer 27, the plate circuit of the tube 23 being also coupled to input circuit 24 through a suitable feed-back coil 28. A filament battery 29 supplies the filament of both tubes through a suitable switch 30 and a plate circuit battery 41 is included in the plate circuit 26 of the detector tube. It is to be understood that this receiving set is typical only and may be substituted by any known or other suitable set capable of receiving radio signals and putting the same on the subscriber's line extensions 13-14 through the repeating coils 19-20. Other antennas such as 43 and 44 are provided for other subscribers' receiving sets, the same as that shown. A normally closed contact 31 on the relay 42 connects the common battery B to the conductor 32 which terminates in a normally open contact 33 in the jack 9 operable to extend the connection of conductor 32 to the signaling conductor 4 to supply battery potential thereto. This signal conductor is arranged to be connected with battery upon energization of the subscriber's line relay through the line relay contact 52, Fig. 1. The relay 42, Fig. 2, also controls the connection of the multiple test circuit conductor 3 to the common battery B through a normally open contact 34 which connection includes a special tone test device of any known or other suitable form, indicated diagrammatically at 35, operable to superpose a characteristic signal current on the test conductor 3. Connected between the signal conductor 4 and ground is a signal lamp 36 mounted near the jack 9 in the manner of the usual telephone line or call lamp. The subscriber at substation A' is provided with a radio broadcast receiving set A¹⁰, multiplied onto the line 69-70 through multiple conductors 5-6 and comprising an arrangement of apparatus elements and circuit connections similar to those of the regular common battery telephone set A' except that the usual switchhook is replaced by a jack J² arranged to cooperate with the plug P² of a loud speaker receiver 64 which takes the place of the usual receiver. Thus the jack J² is so arranged that when engaged by the plug P², the primary coil 60 of the booster coil 61, the transmitter 62 and key 63 will be connected in series across the line through multiples 5-6, and the receiver 64 will be connected in a local series circuit including the secondary winding 65 and condenser 266. A radio broadcasting station indicated generally by the dotted line enclosure 45, is equipped with one or more transmitting devices as indicated at 46 and 49 which may be of any known or other suitable type, preferably a combined relaying and originating apparatus as symbolized by the receiving and

transmitting antennas 47-48 and the input microphone M. The radio broadcasting station 45 is also equipped with a subscriber's telephone substation apparatus A² and broadcast receiving set A²⁰ like the apparatus A' and A¹⁰ and connected with the central station C by line wires 101-102, where they terminate in line terminal apparatus similar to that of the line 69-70. This terminal apparatus, like that of the substation A' and line 69-70, is provided with multiple conductors 221-222-223 and a signaling conductor 224 corresponding in function to conductors 1, 2, 3 and 4 respectively, of the terminal apparatus of substation A'.
70

The broadcasting station 45 is also connected with other telephone central exchanges, furnishing radio broadcast service to its subscribers, through subscriber's substation equipments such as that indicated at 80 x'-x¹⁰. In place of this one line 101-102 may be used in connection with trunk lines not shown for connection with such other exchanges through exchange C. (Fig. 1).
85

In operation, assuming one or more of the broadcasting transmitters at the station 45 to be transmitting, the subscriber at substation A' desiring broadcast service, now connects his broadcast receiving or extension set A¹⁰ to the line by inserting the receiver plug P² in the jack J² which connects his receiver 64 across the line multiples 5 and 6 through the booster coil windings 60-63 and condenser 266 in series, and closes a path for direct current between the multiples 5 and 6 through coil 60, lower spring of jack J², transmitter 62 and signaling key 63.
90

This energizes the subscriber's line relay at the central office in the usual manner by current from the central office, common battery B, conductor 68, right hand winding of relay L', line conductor 69, to subscriber's substation A', line multiple 5, to subscriber's broadcast receiving set A¹⁰ (Fig. 2), coil 60, transmitter 62, contacts of key 63, conductor 6, 70, left hand winding of line relay L' and back to battery B. Actuation of the line relay energizes the line lamp L² by closure of a local circuit which may be traced from common battery B through circuit elements L², 71, 68, and back to battery B. This causes the line lamp L² at the telephone operator's switchboard to glow, but only for a moment, as the subscriber wanting broadcast service will immediately operate his signal key 63 to rapidly open and close his line circuit which causes his line lamp to flicker instead of glowing steadily and so indicate to the telephone operator (Fig. 1) that the subscriber is not calling for a telephone connection.
95

This intermittent actuation of the subscriber's telephone line relay L' also causes a flickering of the lamp 36 (Fig. 2) associated with his broadcast service, multiple jack 9 situated before the broadcast service 100

125
130

operator. This operator perceiving the flickering of the lamp interprets the signal as a call for broadcast service and in answer thereto inserts the actuating plug 10 in the jack 9. This effects the closure of contacts 7-11, 8-12, and 33. Closure of the contacts 7-11, 8-12, connects the battery B (Fig. 2) across the subscriber's line through the repeating coil windings 15-16 and the sleeve supervisory relay 42 which connection may be traced from battery B (Fig. 2) through circuit elements, 15, 13, 11, 7, 1, (into Fig. 1), 69, 5, (into Fig. 2), 60, 62, 6, (into Fig. 1) 70, 2, (into Fig. 2) 8-12, 14, 42, 16, back to battery B. As this completes the circuit including the battery B and the relay 42, this relay is energized and closes the circuit of the cut-off relay L³ (Fig. 1) over a path which may be traced from the common battery B (Fig. 2) through the circuit elements 35, 34, 3, (into Fig. 1), cut-off relay L³, 68, and through ground back to common battery B. Energization of the cut-off relay disconnects the subscriber's line from the telephone line signal apparatus in the usual manner, thus causing the line lamp L' to become deenergized and extinguishing both signal lamps L² and 36. As the cut-off relay is held energized over the test conductor 3 by battery supplied thereto through the special tone test device 35, a telephone operator in testing the line will receive this characteristic tone test instead of the usual click in the ear indicating that the subscriber's line is busy with the special or broadcast service which may or may not be interrupted for telephone service according to the wishes of the subscriber. Assuming the input circuit 24 (Fig. 2) of the subscriber's central office receiving set to be tuned to the frequency of the waves transmitted by the antenna 48, these waves will be received and detected by the detector tube 23, and the audio signals transferred through the intertube audio transformer 27 to the amplifier tube 37, from whence they will pass, amplified through the repeating coils 19-20 onto the subscriber's line multiples 13-14 and consequently out over the subscriber's line to the substation radio receiver A¹⁰. The circuit of the audio signal currents from the secondary winding of the repeating coils 19-20 to the subscriber's substation receiving set A¹⁰ may be traced from common battery B (Fig. 2) through circuit elements 15, 13, 11, 7, 1, (into Fig. 1), 69, 5 (into Fig. 2), 60, 89, 62, 63, 6 (into Fig. 1), 70, 2 (into Fig. 2), 8, 12, 14, relay 42 and its multiple resistance, 16 and back to battery B. The broadcast signal currents passing through the winding 60 of the booster coil 61 are repeated in the coil 65 and included in circuit with the subscriber's broadcast telephone receiver 64 which may be traced from the coil 65 through circuit elements J², P², 64, P², J², 89, 62, 63, 266, back to coil 65.

When the subscriber desires to discontinue the use of the broadcast service, the plug P² (Fig. 2) is pulled which opens the line circuit at the jack 9 deenergizing the relay 42, which in turn connects the battery to the signal circuit conductor 4 through relay contact 31 and energizes the radio service signal lamp 36 over a circuit which may be traced from common battery B through circuit elements 31, 32, 33, 4, 36 to ground and back to common battery B. This causes the lamp 36 to glow steadily indicating to the broadcast service operator that a disconnection is desired whereupon the operator pulls the plug 10 which opens all the contacts of jack 9 and restores the circuits to normal. While, for the sake of simplicity, a manual switch 30 is shown for use in controlling the energization of the tubes 23 and 37 which switch may be closed and opened by the radio operator in connecting and disconnecting the subscriber's line for radio service, it is to be understood that the switch 30 may be replaced by a pair of normally open contacts on the relay 42 for automatically performing this function.

In practice, instead of maintaining the subscriber's central office receiving set always tuned to a given wave length, the set may be provided with means controlled by the radio operator for varying its tuning to permit the subscriber to receive any one of a plurality of programs. In this case the subscriber desiring a change of program would signal the radio operator by flashing the lamp 36 whereupon the operator perceiving the signal and noting the plug 10 to be already in the jack, would connect her listening set with the line by engaging the plug extension terminals 51-52 with the clip contacts 53-54 and, ascertaining the program wanted, would tune the subscriber's receiver to the desired program. Where a group of programs with a separate announcer program is used, as disclosed in my copending application, Serial No. 10,916, filed February 21, 1925, the subscriber's central office receiving set would preferably be normally tuned to the announcer program.

In Fig. 3 is shown a modified arrangement of central office broadcast distributing apparatus which may be substituted for that of Fig. 2, where it is desired to make the central office receiving sets interchangeable with different lines to permit the use of a number of sets less than the number of lines, to permit a quick interchange of sets should one get out of order, to permit program selection by selection of different sets permanently tuned, or to give the subscriber choice of different kinds of sets. Broadly, this arrangement is the same as that of Fig. 2 except that the subscriber's multiple conductors 1, 2 and 4 are arranged to be connected with any one of a number of receiving sets, such as that com-

prising the tubes 23 and 37, through a selector switch 55, while the busy test multiple 3 is arranged to be connected with the battery and tone test device 35 through an off-normal contact 59 of the switch 55. The switch 55 is individual to the subscriber's line having its wipers 56, 57 and 58 connected to the multiples 1, 2 and 4 respectively, and each arranged to cooperate with a bank of contacts 10 for connection with any one of a number of receiving sets, the set here shown being connected with the first contact in each bank through conductors 13, 14 and 32 corresponding to those similarly numbered in Fig. 2. 15 The operator's telephone set 50 is the same as that of Fig. 2 except that it terminates in an ordinary two-conductor plug P^a adapted to engage the jacks 9 to connect the set across the line multiples 1-2. 20 In the operation of the system, using the arrangement of Fig. 3 in place of that of Fig. 2 the subscriber at station A¹⁰ during broadcast service, signals the radio operator by flashing the lamp 36 as before described, 25 whereupon the operator operates the switch 55 to connect the line with an idle radio receiving set. The first movement of the switch causes the closure of the off-normal contact 59 which connects the battery B and tone test device 35 to the test conductor 3 to energize the subscriber's cut-off relay and apply the characteristic radio, busy tone test to the test wire 3, while engagement of the switch arms 56 and 57 with the contacts forming the terminals of the set selected, completes the connection of the secondary winding of the repeating coil of that set to the line multiples which connection may be traced from common battery B (Fig. 3) through circuit elements 15, 13, 56, to line multiple 1, and from multiple 2 through 57, 14, 42 and 16 back to battery B. Should the subscriber desire his set to be tuned to a special program he may signal the radio operator by again flashing 40 the lamp 36, who can ascertain his wants through the use of her telephone set 50 and tune the radio receiving set as required. 45

When the subscriber desires to discontinue the radio service he withdraws the plug of his radio receiver, which opens his line circuit as before described in connection with Fig. 2, and as the relay 42 (Fig. 3) is included in the line circuit it now becomes deenergized permitting the contact 31 to close and energize 50 the lamp 36 in a circuit which may be traced from battery B through circuit elements 31, 32, 58, 4, 36 to ground and back to battery B. The operator observing the continuous glowing of the lamp will now return the switch 55 to the normal position shown which will disconnect the line and open the normally open contact 59 deenergizing the subscriber's cut-off relay and removing the busy test. 60

In the use of either the arrangements of Fig. 2 or Fig. 3, the radio operator may test

the quality of reception furnished by the receiving set connected to the subscriber's line by use of her listening set 50. Also, as the broadcast station 45 is provided with a subscriber's broadcast receiving set A²⁰ connected with the central station, an operator at the station 45 may test the quality of reception of the matter being broadcasted from that station simply by calling for service from the telephone central station, and getting connection for the program to be tested in the same manner as that of any subscriber, for example like that set out in the foregoing description of operation. 70

In Fig. 4 is shown a modified arrangement for switching the subscriber's line into and out of operative connection with a central office receiving set, which is like that of Fig. 2, except that the jack and repeat plug arrangement 9 and 10 is replaced by a jack switch and push-pull button 100, and the connection of the busy test device 35 with the test wire 3 is controlled through a contact on the jack-switch 90 instead of a contact on the supervisory relay 42. In practice a number of the jack switches 90 together with their corresponding line lamps 36 are mounted on a common strip 300, as shown in detail in Figs. 5 and 6. The mounting strip 300 comprises an upper section 301 and a lower section 302 of insulating material in which are embedded the lamp jack springs 304-305 and jack-switch springs 80-120, etc. In front of the spring mounting strip 300 is mounted a face strip or plate 306 provided along its upper portion with apertures 307 through which the lamp 36 may be inserted between the lamp jack-springs 304-305, and in which is mounted the usual telephone lamp jewels 308. A guide rod 309, which has bearing in both the front plate 306 and the back mounting strip 300, carries a wedge bar 310 and an actuating push-pull button 100, the wedge bar 310 being arranged, upon inward movement, to pass between the inner pair of each of the sets of jack-switch springs, spreading the inner springs into contact with their complementary opposed springs as will be clear from the diagram of Fig. 4. To enable the operator to connect her listening set, like that shown at 50 in Fig. 2, with the line, line extension lugs 315 (Figs. 4 and 6) are provided near each button 100, the lugs being mounted in the face plate 306 and connected by wires 316 with the line contact springs 70-80. 105

In the operation of the system using the switching circuits and apparatus of Figs. 4 to 6, the subscriber calls the broadcast operator by flashing the lamp 36 as before described, whereupon the operator presses the button 100 which connects the secondary windings 15-16 of the repeating coils 19-20 in series with the battery B across the subscriber's line multiples. This connection 110 120 125 130

may be traced from battery B (Fig. 4) through circuit elements 15, 13, 110, 70, to line multiples 1 and from line multiple 2 through 80, 120, 14, 42 and its parallel resistance, 16 back to battery B. Closure of the contacts 330 connects the signal wire 4 with the back contact 31 of the relay 42 as, and for the same purpose as that of the similar connection in Fig. 2. The closure of contacts 340 completes a connection from the test or cut-off wire 3 through wire 341 and special tone test device 35 to the ungrounded side of battery B, thus observing the same function as that of the relay contacts 34 of Fig.

15 2. When the subscriber desires to discontinue the broadcast service, he disconnects his broadcast receiving apparatus (Fig. 2) thus causing the broadcast service line-lamp 36 to glow steadily all in the same manner as before described in connection with Fig. 2, whereupon the operator will pull the button 100 restoring the circuits to the normal condition shown.

It is to be noted that in this latter circuit arrangement (Fig. 4), the filament circuit of the subscriber's radio receiving apparatus (here shown fragmentarily for the sake of clearness) is controlled through a normally open contact 350 on the supervisory relay 42, which contact, as will be clearly understood, takes the place of the filament circuit switch 30 of Figs. 2 and 3.

A further modification of the invention which I propose to make use of is to omit 35 the supervisory signal contact 31 from the relay 42 and use the audion tubes such as 37 as supervisory lamps, inasmuch as they glow only during use of the receiving set, the operator being provided with a suitable reflecting system affording observation of the tubes of a group of sets along with identifying 40 numbers or symbols preferably arranged to compensate for any distorting or inverting effect of the reflecting system. In this connection it is to be noted that where the tubes are grouped in close relation they would be properly shielded to prevent inductive or capacity coupling between the same. In the use of the switching arrangement of Fig. 3, 45 this system will afford a simple and direct means for determining what sets are busy, thus avoiding the necessity for extra busy test circuits and signals for the broadcast service operator.

50 It is also to be understood that in all or in certain ones of the radio receiving sets the two audion tubes may be connected as a detector and heterodyne oscillator to form a heterodyne receiver arranged to transmit the resulting beat wave out over the subscriber's 55 line to be detected at the subscriber's substation by suitable apparatus such as a crystal detector.

What I claim is:

65 1. In a system of radio broadcast distribu-

tion, a telephone central station with subscribers' substations and wire lines interconnecting them, a telephone switchboard and a radio switchboard at said central station, radio receiving means at the central station adapted to be connected to an individual subscriber's line and operable to receive and relay radio matter over the line to the substation at a frequency suitable for line transmission, each line connecting means forming a unit in the radio switchboard and comprising the following elements: a line switch, actuating means therefor, a line extension circuit leading therefrom to said radio receiving means, a radio busy test circuit for the line, a radio clearing out signal circuit for the line, and terminal means connected with the line for supervisory purposes.

2. In a system of radio broadcast distribution, a central station with subscribers' substations and wire lines interconnecting them, a telephone switchboard and a radio switchboard at said central station, and a radio receiving set at the central station having its output circuit adapted to be connected to an individual subscriber's line, each line connecting means forming a unit in the radio switchboard and comprising the following elements: a line switch, actuating means therefor, a line extension circuit leading therefrom to said radio receiving means, a radio busy test circuit for the line, a radio clearing out signal circuit for the line, and terminal means connected with the line for supervisory purposes.

3. In a system of radio broadcast distribution, a central office with subscribers' substations and wire lines interconnecting them, a telephone switchboard and a radio switchboard at said central station, a radio receiving set at the central station and means for connecting the lines of said subscribers individually to the output circuit of said set, each line connecting means forming a unit in the radio switchboard and comprising the following elements: a line switch, actuating means therefor, a line extension circuit leading therefrom to said radio receiving means, a radio busy test circuit for the line, a radio clearing out signal circuit for the line, and terminal means connected with the line for supervisory purposes.

4. In a system of radio broadcast distribution, a district broadcast service station, a telephone central station with subscribers' substations and wire lines interconnecting said subscribers and the telephone central station, radio receiving sets at the telephone central station, a telephone switchboard and a radio switchboard at said central station, arranged to receive matter broadcasted from said service station, and means at the telephone central station for operatively connecting one of said receiving sets with the wire line of one of said substations independently

of the other lines, each line connecting means forming a unit in the radio switchboard and comprising the following elements: a line switch, actuating means therefor, a line extension circuit leading therefrom to said radio receiving means, a radio busy test circuit for the line, a radio clearing out signal circuit for the line, and terminal means connected with the line for supervisory purposes.

5 5. In a system of radio broadcast distribution, a district broadcast service station, a telephone central station with subscribers' substations and wire lines connecting the subscribers' stations with the central station, one 10 of said substations being located at the district service station, a telephone switchboard and a radio switch board at said central station, radio receiving sets at the central station arranged to receive matter broadcasted 15 from said service station, and switching means arranged to connect said substations over their respective wire lines each with one 20 of said receiving sets, each line connecting means forming a unit in the radio switchboard and comprising the following elements: a line switch, actuating means therefor, a line extension circuit leading therefrom to said radio receiving means, a radio busy test circuit for the line, a radio clearing 25 out signal circuit for the line, and terminal means connected with the line for supervisory purposes.

6. In a system of radio broadcast distribution, a telephone central station with subscribers' substations and wire lines connecting the substations with the central station, a telephone switchboard and a radio switchboard at said central station, radio receiving sets at the central station, means at the central station for connecting an individual substation line with one of said sets, and means at the central office for selectively tuning said sets for reception at different carrier wave frequencies independently of each other, each 30 line connecting means forming a unit in the radio switchboard and comprising the following elements: a line switch, actuating means therefor, a line extension circuit leading therefrom to said radio receiving means, a 35 radio busy test circuit for the line, a radio clearing out signal circuit for the line, and terminal means connected with the line for supervisory purposes.

7. In a system of radio broadcast distribution, a telephone central station with subscribers' substations and wire lines connecting the substations with the central station, a telephone switchboard and a radio switchboard at said central station, radio receiving sets at the central station, means at the central station for connecting an individual substation line with one of said sets, operator's tuning means at the central station for tuning the sets to different frequencies and means 40 at the central station for determining when a

set is in tune with a desired frequency, each line connecting means forming a unit in the radio switchboard and comprising the following elements: a line switch, actuating means therefor, a line extension circuit leading therefrom to said radio receiving means, a radio busy test circuit for the line, a radio clearing out signal circuit for the line, and terminal means connected with the line for supervisory purposes.

8. In a system of radio broadcast distribution, a telephone central station with subscribers' substations and wire lines connecting the substations with the central station, a telephone switchboard and a radio switchboard at said central station, radio receiving sets at the telephone central station, and means at the central station for connecting the wire line of one of said substations with any one of said receiving sets selectively, each line connecting means forming a unit in the radio switchboard and comprising the following elements: a line switch, actuating means therefor, a line extension circuit leading therefrom to said radio receiving means, a radio busy test circuit for the line, a radio clearing out signal circuit for the line, and terminal means connected with the line for supervisory purposes.

9. In a system of radio broadcast distribution, a telephone central station with subscribers' substations and wire lines connecting the substations with the central station, a telephone switchboard and a radio switchboard at said central station, radio receiving sets at the telephone central station, means for interchangeably connecting said wire lines and said receiving sets and means at the central station for tuning said receiving sets, each line connecting means forming a unit in the radio switchboard and comprising the following elements: a line switch, actuating means therefor, a line extension circuit leading therefrom to said radio receiving means, a radio busy test circuit for the line, a radio clearing out signal circuit for the line, and terminal means connected with the line for supervisory purposes.

10. In a system of radio broadcast distribution, a telephone central station with subscribers' substations and wire lines connecting the substations with the central station, a telephone switchboard and a radio switchboard at said central station, radio receiving sets at the central station, a telephone operator's line signal and a radio operator's line signal for each line at the central office, different means at each substation for differently actuating its telephone line signal and radio line signal respectively, means at the central station for connecting a line with one of said receiving sets independently of said other lines and an operator's listening set arranged to be connected to the connected line at the radio switchboard and operable to re-

produce the signals received through said connected radio receiving set.

11. In a system of radio broadcast distribution, a telephone central station with subscribers' substations and wire lines connecting the substations with the central station, a telephone switchboard and a radio switchboard at said central station, radio receiving sets at the central station, each including detector and amplifying means, for receiving modulated radio waves and delivering the audio frequency modulations thereon duly amplified, the output circuits of said sets being individually associated with subscribers' lines, and line terminal apparatus on the radiowire switchboard for each of said substation lines at the central station comprising a line signal and a normally open switch wholly individual to the line and operable upon closure to connect its line through its corresponding output circuit with one of said receiving sets.

12. In a system of radio broadcast distribution, a telephone central station with subscribers' substations and wire lines connecting the substations with the central station, a telephone switchboard and a radio switchboard at said central station, radio receiving sets at the central station each including detector and amplifying means, for receiving modulated radio waves and delivering the audio frequency modulations thereon duly amplified, the output circuits of said sets being individually associated with subscribers' lines, and line terminal apparatus on the radiowire switchboard at the central station for each of said substation lines consisting of a unitary assemblage comprising a line signal, a switch and a pair of line testing terminals, said testing terminals being permanently connected with the line and said switch being arranged upon actuation to connect the line through its corresponding output circuit with a receiving set, together with an operator's test circuit arranged to be connected with any pair of said testing terminals independently of the switch.

13. In a system of radio broadcast distribution, a telephone central station with subscribers' substations and wire lines connecting the substations with the central station, a telephone switchboard and a radio switchboard at said central station, line switches in said telephone switchboard for interconnecting the lines in pairs for conversation, radio receiving sets at the central station, each including detector and amplifying means, for receiving modulated radio waves and delivering the audio frequency modulations thereon duly amplified, the output circuits of said sets being individually associated with subscribers' lines, and a line switch in the radio switchboard for each line arranged to connect its line through its corresponding output circuit with a receiving set.

14. In a system of radio broadcast distribution, a telephone central station with subscribers' substations and wire lines connecting the substations with the central station, radio receiving sets at the central station and line terminal apparatus at the central station for each of said substation lines consisting of a unitary assemblage comprising a line signal, a switch and a pair of line testing terminals, said testing terminals being permanently connected with the line and said switch being arranged upon actuation to connect the line with a receiving set, together with an operator's test circuit arranged to be connected with any pair of said testing terminals, together with means for indicating to an operator the use or non-use of said sets.

15. Line terminal switching and signaling apparatus comprising a plurality of units mounted on a common mounting strip, each unit comprising a line signal, a line switch, a push-pull actuating button operable to connect and disconnect the line circuit to and from an extension circuit, to connect and disconnect a busy test circuit for the line, and to connect and disconnect a clearing out circuit for the line signal, respectively, and a pair of exposed line test terminals situated one on either side of the push pull button and permanently connected one with each line conductor.

16. In a system of radio broadcast distribution, a central distributing station, a plurality of subscribers' stations connected therewith by wire lines, service terminals for said lines at the central station and means to effect connection with the lines through said terminals, an audio frequency receiving instrument at a subscriber's station, a radio frequency receiving instrument comprising a detector tube and amplifying means at the central distributing station, means connecting the output of said radio receiving set directly and individually to the subscriber's line without going through said service terminals, with means at the subscriber's station to connect and disconnect said audio receiving apparatus to and from the line.

17. In a system of radio broadcast distribution, a central distributing station, a plurality of subscribers' stations connected therewith by wire lines, service terminals for said lines at the central station and means to effect connection with the lines through said terminals, an audio frequency receiving instrument at a subscriber's station, a radio frequency receiving instrument comprising a detector tube and amplifying means at the central distributing station, means connecting the output of said radio receiving set directly and individually to the subscriber's line without going through said service terminals, with means at the subscriber's station to connect and disconnect said audio receiving apparatus to and from the line, and

other means actuated in the operation of said connecting means adapted to close and open the line respectively.

18. The radio broadcast distributing system described in claim 16, in which the central station radio receiving instrument is individual to and permanently associated with the line circuit from the central station to the subscriber's station.

19. The radio broadcast distributing system described in claim 16, with the added element of a broadcasting station equipped with a wired line circuit extending to the central distributing station, and a radio receiving set similar to the subscribers' sets thereto connected, whereby the broadcasting station may receive and listen to its own broadcast matter in the same manner and under the same conditions as the subscribers.

20. The radio broadcast distributing system described in claim 16, in which a plurality of subscribers' stations are equipped as stated, each station having a wire circuit extending to the central station, with a plurality of individual radio receiving sets at said central station connected to said wire circuits, and means whereby an operator at the central distributing station may listen in and supervise the transmission over each subscriber's line.

In testimony whereof I hereunto affix my signature.

EDWARD E. CLEMENT.
